(57) **CLAIM**

The ornamental design for detergent container with massage brush, as shown and described.

DESCRIPTION

FIG. 1 is a front elevational view of a detergent container with massage brush, showing our new design;

FIG. 2 is a side view thereof;

FIG. 3 is a rear elevational view thereof;

FIG. 4 is a top plan view of the cover thereof;

FIG. 5 is a side fragmentary view with the cover removed showing the internal container;

FIG. 6 is a rear elevational fragmentary view with the cover removed showing the internal container; and,

FIG. 7 is a top plan fragmentary view with the cover removed showing the internal container.
